United States Patent Office

Des. 195,697
Patented July 16, 1963

195,697

JUG

Clarence A. Price, Ann Arbor, Mich., assignor to Hoover
Ball and Bearing Company, Ann Arbor, Mich., a corporation of Michigan

Filed July 3, 1961, Ser. No. 65,790

Term of patent 14 years

(Cl. D58—5)

my new design;

FIGURE 2 is an end elevational view thereof; and FIGURE 3 is a top plan view thereof.

I claim:

The ornamental design for a jug, as shown.
